UNITED STATES PATENT OFFICE.

MANUEL R. RODRIGUES, OF BROOKLYN, NEW YORK.

ELECTRIC RECEPTACLE.

1,314,218.

Specification of Letters Patent. Patented Aug. 26, 1919.

Application filed November 14, 1918. Serial No. 262,520.

To all whom it may concern:

Be it known that I, MANUEL R. RODRIGUES, a citizen of the United States of America, and a resident of the borough of Brooklyn 5 of the city of New York, in the county of Kings and State of New York, have invented a certain new and useful Electric Receptacle, of which the following is a specification, the same being a full, clear and exact description 10 of the invention, such as will enable others skilled in the art to which it appertains to make and use the same.

This invention relates to improvements in electrical devices, and in particular to wall 15 receptacles or attachment plug fittings and the like, which are adapted to be used in connection with appliance plugs and indicator or signal devices, whereby the latter may be readily and quickly attached to, or detached from, the source of supply. It has 20 for its object to provide an inexpensive and compact receptacle constructed and arranged to be attached in any desired position on a wall surface or other suitable support, and it consists in the construction, arrangement and operation of parts as hereinafter set forth.

With these and other objects in view, I have devised a convenient, novel and useful 25 receptacle which I will now describe:

In the drawings, illustrative of one embodiment of the invention, which accompany and form a part of this specification,

Figure 1 represents an elevation of a receptacle in which my invention is embodied;

Fig. 2 is a vertical section thereof; and

Fig. 3 is a view of the electric connections used in the same.

Like numerals of reference indicate like 40 parts in all the views.

In the use of electric utensils of various descriptions, and especially in the employment of electrical implements by persons that are often unfamiliar with the dangerous 45 character of their use, accidents are liable to happen, and in order to surround the said devices with a safeguard against such occurrences I have constructed a receptacle whereby a signal may be given or indicated 50 at the time, and during the continuance, of the closing of the circuit through the same, thereby giving a warning to the user thereof of the danger attendant upon the employment of whatever implement may happen at 55 the time to be connected therewith.

Referring particularly to the drawings, 1

denotes the body of a receptacle of the class described having an inlet 31 and closure attachment means, as lugs 3, which closure 2 may be detachably secured to the receptacle 60 by suitable attaching elements, as screws 4.

A socket for the signal or indicating means—in the present instance a pilot lamp—and also sockets 6 and 7 for fuses are fastened to the inner face of the closure 65 and have portions extending through the outer face of the same, whereby, by the insertion in the respective supplemental electric lamp socket 34 and the supplemental fuse sockets 35' and 36' of the lamp 35 and 70 the fuses 21, the said sockets will be rendered operative when suitably connected with the circuit wires contained within the receptacle.

A switch 9, which is preferably a double pole one of the rotary or flush type, and 75 also the socket or chamber 8 of a preferably surface or flush attachment plug device having spring contacts 33, are likewise secured to the inner face of the closure and have portions extending through the outer face 80 thereof, whereby the switch 9 may be operated by the manipulation of the buttons 23 and 24 thereof, and the appliance plug 26 connected in circuit by the insertion in the orifice 25, formed in the exterior face 22 of 85 its socket 8, of the knife blade contacts 27 of the said connecting cap or appliance plug which blades engage the spring contacts 33. Any suitable or preferred means may be employed for securing the said sockets and 90 switch in the desired position, as for example by the use of lugs 29 formed thereon and attaching elements, as screws 30.

The fuses 21 may be inclosed if desired 95 by being incased within a cover 28 hinged at 28' and held in closed position by fastening elements as screws 28''.

The electric cord 32 enters the receptacle through the inlet 31 and one conductor 10 thereof extends to the fuse socket 6 and 100 thence by the wire 11 to one contact of the switch 9. From the said switch one wire 15 runs in one direction, as at 13, to the pilot lamp socket and in another direction, as at 14, to the appliance plug socket 8. 105

Another conductor of the cord 32 extends from said cord to the fuse socket 7 and thence by the wire 16 to the other contact of the switch 9. From the said switch one wire 40 runs in one direction, as at 12, to the pilot lamp socket, and in another direction, as at 18, to the appliance plug socket 8. When

the switch is in the on position and the indicator is in its socket, the said switch and all of the sockets will be in circuit and the pilot lamp will be connected in parallel with 5 the appliance plug socket.

When the parts are in this position, upon the cap 26 being inserted in the orifice 25 of the appliance plug socket, the knife blade contacts 27 become energized by the engagement thereof with the spring contacts 33, and the conductors 19 and 20 of the cord 26 of the appliance plug may be utilized to operate lighting devices, fans, motors, ironing implements, surgical or cooking appliance, etc., at will.

It will be noted that the parts are so arranged that none of the electric connections within the receptacle can be changed without removing the closure from the body portion thereof, and that when the switch is in the on position and the indicator is inserted in its socket, the said indicator will be in circuit whether the appliance plug is attached to its socket or not.

25 I wish it to be understood that I do not desire to be limited to the particular use or the exact details of construction shown and described, for obvious modifications will occur to persons skilled in the art.

30 What I claim as my invention is:—

1. A receptacle of the class described, comprising a body portion having an inlet for electric conductors, and closure attaching means, a cover forming a closure for the receptacle, sockets for an indicator, for at least one fuse, and for an appliance plug, a switch attached to the interior face of the closure, the latter being provided with openings for the switch buttons and the closure 35 being also provided with orifices in line axially respectively with the indicator, fuse and plug sockets, to allow the indicator, plug and fuse to be placed in operative position in their sockets and removed without having

access to the interior of the receptacle, means 45 for securing the closure to the said attaching means to hold the former in protective position to prevent any tampering with the said sockets without removing the closure, and connections so arranged that when the 50 switch is in an on position and the indicator is inserted in its socket, the said indicator will be in circuit whether the appliance plug is attached to its socket or not.

2. A receptacle of the class described, 55 comprising a body portion having an inlet for electric conductors, and closure attaching means, a cover forming a closure for the receptacle, sockets for an indicator, for at least one fuse, and for an appliance plug, 60 a switch attached to the interior face of the closure, the latter being provided with openings for the switch buttons and the closure being also provided with orifices in line axially respectively with the indicator, and 65 plug sockets, the parts being arranged so as to allow the indicator, plug and fuse to be placed in operative position in their sockets and removed without having access to the interior of the receptacle, means for securing 70 the closure to the said attaching means to hold the former in protective position to prevent any tampering with the said sockets without removing the closure, and connections so arranged that when the switch is in 75 an on position and the indicator is inserted in its socket, the condition of the circuit will be shown by the indicator, in combination with means to inclose the said fuse.

In testimony of the foregoing specification I do hereby sign the same in the borough of Brooklyn of the city of New York, in the county of Kings and State of New York this 8th day of November, 1918.

MANUEL R. RODRIGUES.
